US00D479542S

(12) **United States Design Patent** (10) Patent No.: **US D479,542 S**
Lannoch (45) Date of Patent: ** Sep. 9, 2003

(54) **PLANETARY GEAR WITH SQUARE FLANGE**

(75) Inventor: **Hans-Jürgen Lannoch**, Linkenheim-Hochstetten (DE)

(73) Assignee: **SEW-Eurodrive GmbH & Co.**, Bruchsal (DE)

(**) Term: **14 Years**

(21) Appl. No.: **29/170,220**

(22) Filed: **Nov. 1, 2002**

(30) **Foreign Application Priority Data**

May 2, 2002 (DE) 4 02 03 875

(51) LOC (7) Cl. **15-09**

(52) U.S. Cl. **D15/148**

(58) Field of Search D15/148, 149; 74/395, 411, 640; 475/83, 331-335, 345

(57) **CLAIM**

The ornamental design for a planetary gear with square flange, as shown and described.

DESCRIPTION

FIG. 1 is a perspective view showing my new design of a planetary gear with square flange;

FIG. 2 is an output back view thereof;

FIG. 3 is a side elevational view thereof;

FIG. 4 is a bottom view thereof; and,

FIG. 5 is an input front view thereof.
